[57] CLAIM

The ornamental design for the light fixture for recreational vehicles, as shown and described.

DESCRIPTION

FIG. 1 is a perspective view of a light fixture embodying the design;

FIG. 2 is a top plan view thereof;

FIG. 3 is a side elevation thereof;

FIG. 4 is a front elevation thereof;

FIG. 5 is a rear elevation thereof;

FIG. 6 is a bottom plan view thereof;

FIG. 7 is a front elevation showing a second embodiment thereof;

FIG. 8 is a bottom plan view of the embodiment shown in FIG. 7; and,

FIG. 9 is a perspective view thereof.

The side opposite FIG. 3 is a mirror image of that figure. The embodiments of FIGS. 7, 8 and 9 is identical to that shown in FIGS. 1-6 inclusive, except for the rectangular area at the bottom of the lens, which depicts the outer visual appearance of a series of adjacent angular surfaces in the lens.
